LAYING CAGE DIVIDER

Gerald L. Kitson, 9709 Belding Road,
Rockford, Mich. 49341

Filed Mar. 1, 1971, Ser. No. 119,980

Term of patent 14 years

Int. Cl. D30—02

U.S. Cl. D30—1

FIG. 1 is a front elevational view of a laying cage divider embodying my new design; and

FIGS. 2, 3 and 4 are end, top, and end views respectively, of the laying cage divider shown in FIG. 1.

I claim:

The ornamental design for laying cage divider, as shown.
